CLAIM

The ornamental design for a home air diffuser, as shown and described.

DESCRIPTION

FIG. 1 is a perspective view of a home air diffuser showing a new design;

FIG. 2 is a front view of the home air diffuser of FIG. 1;
FIG. 3 is a rear view of the home air diffuser of FIG. 1;
FIG. 4 is a left side view of the home air diffuser of FIG. 1;
FIG. 5 is a right side view of the home air diffuser of FIG. 1;

FIG. 6 is a top view of the home air diffuser of FIG. 1; and,
FIG. 7 is a bottom view of the home air diffuser of FIG. 1.
The broken lines shown in FIGS. 4-7 are for the purpose of
illustrating environmental structure and form no part of the
claimed design.
